BACK-FIRE RELEASE FOR INTERNAL
COMBUSTION ENGINESWilliam L. McGrath, Elmira, N. Y., assignor to
Eclipse Machine Company, Elmira, N. Y., a cor-
poration of New York

Application October 31, 1931, Serial No. 572,249

11 Claims. (Cl. 290—38)

This invention relates to a back-fire release for internal combustion engines and more particularly a device for preventing damage to engine starting mechanism due to backward rotation of such engines.

It is well known that the actuation of an engine starting mechanism when the engine is rotating backward causes heavy stresses to be developed which may cause failure of the parts subjected thereto. When controlling devices are employed for facilitating or instituting the actuation of the starting mechanism, it therefore becomes important to automatically prevent such actuation during backward rotation of the engine.

It is an object of this invention to provide a novel device for rendering the engine starting mechanism inoperative as a result of back-fire or backward rotation of the engine.

Another object of the invention is to provide such a device which retains the starting mechanism in its inoperative condition regardless of the cessation of the back-firing or backward rotating condition.

A further object is to provide such a device embodying manual means for again rendering the starting mechanism operative.

Further objects and advantages will become apparent to those skilled in this art from the following description taken in connection with the accompanying drawing in which:—

Fig. 1 is a semi-diagrammatic showing of a preferred embodiment of the invention as used in conjunction with an ordinary starting relay circuit, the back-fire release device being sectioned on line 1—1 of Fig. 3;

Fig. 2 is a similar view of the device as used in conjunction with a known form of automatic starting mechanism the parts of the back-fire release being shown in the positions which they assume as a result of back-fire; and

Fig. 3 is a cross section of the back-fire release on the line 3—3 of Fig. 1.

In Fig. 1 of the drawing there is illustrated an electrical starting system for an internal combustion engine (not shown) including a battery 1 grounded at 2 and connected by a lead 3 to an electromagnetic starting switch indicated generally by the numeral 4. This starting switch comprises a movable switch member 5 adapted to bridge contacts 6 and 7, thus completing a circuit through lead 8 to the starting motor SM which is grounded at 9. The switch plunger 5 is adapted to be actuated by a solenoid 11 which is embodied in a control circuit including a bat-

tery lead 12, manual switch 13, lead 14, back-fire release device 15, lead 16 and ground lead 17, the arrangement being such that closure of the control circuit causes energization of solenoid 11 to close the starting circuit and energize 60 the starting motor.

The back-fire releasing device indicated generally at 15 is mounted on the intake manifold 22 of the engine to be started, and comprises a casing 18 containing a metallic diaphragm 19 forming a closed chamber 21 which is in communication with the intake manifold 22 of the engine as by means of a passage 23 in an extension 24 of casing 18 which is threaded in an opening in said manifold. A pair of insulated binding posts 25 and 26 are mounted in the top of casing 18, the binding post 25 being connected to a stationary contact member 27, and binding post 26 being connected to a spring contact member 28 which is normally in engagement with contact 27. The outer end of spring contact 28 is arranged to bear on a post 29 of insulating material which rests on the center of the diaphragm 19, and is retained in position by suitable means such as a pilot pin 30 traversing the contact member 28 and entering the post 29. The diaphragm is slightly dished so as to form a snap diaphragm which maintains its position as illustrated in either Fig. 1 or Fig. 2 until it is moved into its other position by some extraneous force.

When the diaphragm 19 is in its lower position as illustrated in Fig. 1, the spring contact 28 is allowed to rest on the fixed contact 27, thus completing the circuit through the back-fire release. When the diaphragm is raised to its upper position as shown in Fig. 2 by pressure within the intake manifold 22, the post 29 is arranged to move the spring contact 28 out of engagement with the fixed contact 27 95 as there illustrated which position will be maintained until pressure is applied to the upper surface of the diaphragm to force it to its lower position. In Fig. 1, a plunger 31 is provided for manually returning the diaphragm to its lower position in order to allow the contacts 27 and 28 to close.

In Fig. 2 there is illustrated a second embodiment of the invention in which the back-fire releasing device is used in conjunction with an automatic starting mechanism for causing the engine to be cranked whenever forward rotation thereof ceases. An electrical starting system similar to that shown in Fig. 1 is there illustrated comprising a battery 41 grounded at 42 110

and connected by a lead 43 to an automatic starting device indicated generally at 44 and comprising a switch plunger 45 adapted to bridge contacts 46 and 47 to complete a circuit to the 5 starting motor SM through lead 48 and ground connection 49. The switch plunger 45 is adapted to be actuated by a solenoid 51 which is embodied in a control circuit comprising lead 52, ignition switch 53, lead 54, back-fire release device 55, lead 56 and lead 57. This circuit is similar to the control circuit illustrated in Fig. 1, but the lead 57 of solenoid 51 instead of being connected directly to the ground is grounded through the generator G driven by the internal 10 combustion engine. It will thus be seen that when the engine starts, the solenoid 51 will be deenergized by reason of the counter E. M. F. of the generator opposing the battery voltage. The switch 53 may therefore be left closed at all 15 times while the engine is running and hence may be also used as the ignition switch for the engine.

The back-fire release device 55 is similar in all respects to the back-fire release 15 except that the manual plunger 31 has been omitted. In place of this plunger, a push button 58 is provided which may be located in a position convenient to the operator and which when depressed shunts out the back-fire release device 25 55 and causes actuation of solenoid 51 when the ignition switch 53 is closed. The consequent cranking of the engine causes a partial vacuum to be created in the intake manifold 22 whereby the diaphragm 19 is sucked down to its lower 30 position, allowing the contacts 27 and 28 to close, whereupon the automatic starting mechanism 35 is again placed in operative condition.

In the operation of the embodiment of the invention disclosed in Fig. 1, closure of the manual switch 13 causes actuation of solenoid 11 to 40 close the starting switch and cause the engine to be cranked. If the engine starts successfully, the operator opens the switch 13 and the starting switch is thereupon returned to normal position. If the engine should back-fire, however, pressure is immediately built up in the intake 45 manifold 22 by the backward rotation of the engine whereby the diaphragm 19 is moved to its upper position, breaking contacts 27 and 28 and rendering the solenoid 11 inoperative whereby engagement of the starter during backward rotation of the engine is prevented. When the 50 backward rotation has ceased, the operator presses the plunger 31 to return the diaphragm 55 19 to its normal position whereupon switch 13 may be again closed and the starting operation repeated.

In the embodiment of the invention illustrated in Fig. 2, closure of the switch 53 by the operator closes the ignition circuit and also the control circuit through the solenoid 51 whereby the starting switch member 45 is moved to closed position to cause the engine to be cranked. If the engine starts properly, the counter E. M. F. of generator G opposes the flow of battery current through the solenoid 51, thus deenergizing said solenoid and causing the starting switch to be opened. If the engine should back-fire, 65 however, the diaphragm 19 of the back-fire release 55 is forced upward by the pressure in the intake manifold as above described thus breaking the control circuit and opening the starting switch. In order to reactivate the starting mechanism it is merely necessary for the opera- 70 75

tor, after the backward rotation has ceased to depress the push button 58, thus energizing solenoid 51 and causing the cranking operation to be repeated. The consequent suction created in the intake manifold 22 causes the diaphragm 80 19 to return to its normal position whereupon the push button 58 may be released and the automatic starting mechanism will proceed to function in its usual manner.

Although but two embodiments of the invention have been shown and described in detail, it will be understood that other embodiments are possible and various changes may be made in the construction and arrangements of the parts and certain features thereof may be used without other features without departing from the spirit of the invention as defined in the claims appended hereto.

What is claimed is:—

1. In combination with an internal combustion engine, starting mechanism therefor including a starting motor, manually controllable means for actuating said starting motor, means responsive to backward rotation of the engine for rendering said actuating means inoperative, and manually controllable means for returning the actuating means to operative condition.

2. In combination with an internal combustion engine, starting mechanism therefor including a starting switch, manually controllable means including a control circuit for actuating said starting switch, means responsive to backward rotation of the engine for opening the control circuit, and manually controllable means for closing the control circuit.

3. In combination with an internal combustion engine, starting mechanism therefor including a starting switch, manually controllable means including a control circuit for actuating said starting switch, a pair of contacts in said control circuit, means responsive to backward rotation of the engine for opening said contacts and manually controllable means for causing said contacts to be closed.

4. In combination with an internal combustion engine having a fuel intake system, starting mechanism therefor, means responsive to positive pressure higher than atmospheric pressure in said intake system of the engine for preventing the operation of the starting mechanism and manually controllable means for rendering the starting mechanism operative.

5. In combination with an internal combustion engine having a fuel intake system, starting mechanism therefor including a starting switch, means including a control circuit for closing said starting switch, means responsive to pressure in said intake system of the engine for opening said control circuit, and responsive to forward rotation of the engine to close said opening in the control circuit, and manually controllable means to institute forward rotation of the engine.

6. In combination with an internal combustion engine, automatic starting mechanism therefor including a starting switch, manually controllable means for automatically closing said switch in case of engine stall, means actuated by backward rotation of the engine for preventing automatic closure of the starting switch and manual means for resetting the starting mechanism for automatic operation.

7. In combination with an internal combustion engine, automatic starting mechanism therefor including a starting switch, manually

controllable means for automatically closing said switch in case of engine stall, means actuated by backward rotation of the engine for preventing automatic closure of the starting switch, 5 said preventing means being actuated by forward rotation of the engine to again permit automatic actuation of the starting mechanism, and manual means for causing actuation of the starting mechanism to crank the engine.

10 8. In combination with an internal combustion engine having a fuel intake system, starting mechanism therefor including a starting switch, manually controllable means for actuating said starting switch including a control circuit, means 15 for automatically energizing said control circuit in case of engine stall, and means actuated by pressure in said intake system of the internal combustion engine for preventing energization of said control circuit, said preventing means being actuated by suction in the intake system 20 to reestablish automatic actuation of the control circuit.

25 9. In combination with an internal combustion engine having a fuel intake system, starting mechanism therefor including a starting switch, manually controllable means for actuating said starting switch including a control circuit, means 30 for automatically energizing said control circuit in case of engine stall, means actuated by pressure in said intake system of the internal combustion engine for preventing energization of said control circuit, said preventing means being actuated by suction in the intake system to re-establish automatic actuation of the control 35 circuit.

cuit, and manual means independent of said preventing means for initiating the actuation of the starting mechanism.

10. In combination with an internal combustion engine having a fuel intake system, starting mechanism therefor including a starting switch, manually controllable means for actuating said starting switch including a control circuit, means for automatically energizing said control circuit in case of engine stall, a pair of contacts in said control circuit, a snap diaphragm for opening said contacts in response to pressure in the intake system of the internal combustion engine, and manual means for returning the contacts to closed position. 80

85 11. In combination with an internal combustion engine having a fuel intake system, starting mechanism therefor including a starting switch, manually controllable means for actuating said starting switch including a control circuit, means for automatically energizing said control circuit in case of engine stall, a pair of contacts in said control circuit, a snap diaphragm for opening said contacts in response to pressure in said intake system of the internal combustion engine, and closing said contacts responsive to suction in said intake system, and manual means for initiating the operation of the starting mechanism when said contacts are open whereby the suction in the intake system serves to reclose said contacts and reestablish automatic operation of the starting mechanism. 90 95 100 105
